UNITED STATES PATENT OFFICE.

PETER SKANSE, OF MINNEAPOLIS, MINNESOTA.

TRAFFIC SIGNAL.

Application filed December 12, 1921. Serial No. 521,685.

To all whom it may concern:

Be it known that I, PETER SKANSE, a citizen of the United States, residing at Minneapolis, in the county of Hennepin and State of Minnesota, have invented certain new and useful Improvements in Traffic Signals; and I do hereby declare the following to be a full, clear, and exact description of the invention, such as will enable others skilled in the art to which it appertains to make and use the same.

My invention relates to traffic signals and, more particularly, to such signals applied to vehicles, and has for its object to provide an extremely simple and highly efficient traffic signal that is easy to operate, and while intended for use in connection with all kinds of vehicles, it is especially adapted for use with vehicles having closed bodies or cabs.

To the above end, generally stated, the invention consists of the novel devices and combinations of devices hereinafter described and defined in the claims.

25 Referring to the drawings:

Fig. 1 is a fragmentary perspective view of a closed automobile having the invention applied thereto and with the semaphore arm indicated in an inoperative position by means of broken lines, and in an operative position by means of full lines;

Fig. 2 is a view partly in elevation and partly in horizontal section taken on the line 2—2 of Fig. 1, with the semaphore arm 35 adjusted to an inoperative position;

Fig. 3 is a perspective view of the invention removed from the automobile and showing the same in an inoperative position by means of broken lines, and in an operative position by means of full lines; and

Fig. 4 is a perspective view of the lock plate.

The numeral 5 indicates the front left-hand post of the body 6 of a closed automobile. The improved traffic signal includes, as shown, a flat semaphore arm 7 rigidly secured to one end of a horizontal shaft 8 by a pair of opposing nuts 9. This shaft 8 extends longitudinally in respect to the automobile and is rotatably mounted in a bearing formed in the post 5 and supports the semaphore arm 7 just in front of the post 5 for swinging movement from a depending inoperative position, as shown by broken lines in Figs. 1 and 3 and full lines in Fig. 2, to an outstanding horizontal posi-

tion in which it projects transversely of the automobile, as shown in Figs. 1 and 2 by full lines.

On the inner face of the post 5 is a lock plate 10, secured by screws 11 and in the form of a disk having an axial bore through which the shaft 8 extends, and which lock plate also affords a bearing for said shaft. The inner end portion of the shaft 8 is 65 bent laterally to afford an operating handle 12, the outer end portion of which is folded upon itself and spaced thereapart, in the plane of the shaft 8, to afford a yielding lock arm 13. The outer end of the lock 70 arm 13 is arranged to enter, by a spring action, either one of the two radially disposed lock notches 14, which extend at right angles to each other, and thereby yieldingly hold the semaphore arm in a depending 75 inoperative position or a horizontal operative position.

At its free end portion, the lock arm 13 is bent laterally into parallel arrangement with the shaft 8 and then again bent laterally into parallel arrangement with the operating handle 12, but spaced apart therefrom, to afford a releasing arm 15 for said lock arm. By drawing the releasing arm 15 toward the operating handle 12, the lock 85 arm 13 may be sprung out of the engaged lock notch 14 to release the shaft 8 and thereby permit the same to be turned by the operating handle 12 to swing the semaphore arm 7 from an inoperative position to an 90 operative position, and vice versa.

The semaphore arm 7 is tapered toward its free end to increase the width thereof and thereby make the same more conspicuous. To further make the semaphore arm 95 7 more attractive, the same is provided with a supplemental section 16 pivoted to the back of the semaphore arm 7 and gravity-held in an upright position by locating its pivot off center. When the semaphore arm 100 7 is in an inoperative position, its supplemental section 16 is entirely covered thereby, and when the semaphore arm 7 is in an operative position, said supplemental section extends transversely thereof, as shown 105 by full lines in Fig. 1.

To operate the semaphore arm 7, it is only necessary to take hold of the handle 12 and, at the same time, grasp the releasing arm 15 and draw the same toward the handle 12 110 to spring said arm out of the engaged lock notch 14. Then, by turning the handle 12

to rotate the shaft 8, the semaphore arm 7 may be swung to its desired position. After the initial movement of the shaft 8, the releasing arm 15 may be released so that it will spring into interlocking engagement with the next lock notch 14 and thereby properly position the semaphore arm 7.

Obviously by adjusting the nuts 9 on the shaft 8, said shaft may be adjusted endwise to vary the tension with which the lock arm 13 engages the lock plate 10.

The above described invention, while extremely simple and of comparatively small cost to manufacture, can be very quickly applied to an automobile.

What I claim is:—

1. The combination with a shaft and a bearing element applicable to a car body, of a semaphore arm attached to one end of the shaft, the other end of the shaft being bent laterally to afford an operating handle, said operating handle being folded upon itself to afford a yielding lock arm arranged to engage the bearing element and hold the semaphore arm where set, said shaft, semaphore arm and handle being connected for common turning movement.

2. The combination with a shaft and a bearing element applicable to a car body, of a semaphore arm attached to one end of the shaft, the other end of the shaft being bent laterally to afford an operating handle, said operating handle being folded upon itself to afford a yielding lock arm arranged to engage the bearing element and hold the sema-

phone arm where set, said lock arm being folded between itself and the operating handle to afford a releasing arm for the lock arm, said shaft, semaphore arm and handle being connected for common turning movement.

3. The combination with an endwise movable shaft and a bearing element applicable to a car body, of a semaphore arm attached to one end of the shaft, the other end of the shaft being bent laterally to afford an operating handle, said operating handle being folded upon itself to afford a yielding lock arm arranged to engage the bearing element and hold the semaphore arm where set, said lock arm being folded between itself and the operating handle to afford a releasing arm for the lock arm, said shaft, semaphore arm and handle being connected for common turning movement.

4. The combination with a shaft and a lock plate applicable to a car body, said lock plate having circumferentially spaced lock notches, of a semaphore arm attached to one end of the shaft, the other end of the shaft being bent laterally to afford an operating handle, said operating handle being folded upon itself to afford a yielding lock arm adapted to enter said lock notches and hold the semaphore arm in different set positions, said shaft, semaphore arm and handle being connected for common turning movement.

In testimony whereof I affix my signature.

PETER SKANSE.
